THREAD ADVANCING REEL

William V. Henry, Candler, N. C., assignor to
 American Enka Corporation, Enka, N. C., a corporation of Delaware

Application July 6, 1949, Serial No. 103,259

10 Claims. (Cl. 28—71.7)

1

This invention relates to thread storage, thread advancing devices and more particularly to a cantilever supported thread storage, thread advancing device of simple design which is capable of easy adjustment to permit variable thread storage time thereon.

In the art relating to thread storage, thread advancing devices there are to be found reels comprised of a plurality of circumferentially arranged slats or rods with means to cause alternate rods to execute an operation each cycle of which includes engaging a coil of thread, advancing that coil toward one end of the reel, releasing the coil and finally returning to the starting position. In these machines the rods are subjected to concurrent reciprocation in both radial and axial directions at different frequencies and the mechanisms for causing such movements have been so complex to construct and install as to render the reels of doubtful commercial value.

For example, in the patent to Hellbach No. 2,469,767 there is described a cantilever supported reel including a fixed set of bars alternately spaced with a set of bars mounted for both axial and radial reciprocation. The members of the movable set of bars engage cam faces which cause them to execute radial and axial movement to and from thread supporting and advancing position. The strokes of the bars both axially and radially are fixed in amplitude so that the only way to get control of storage time at any given peripheral speed of the reel is by driving the cam in some relation to the rods so that the number of cycles of movement of each rod in a bodily movement of 360° is varied. This type of adjusting apparatus inherently includes some type of change speed mechanism for driving the cams and is therefore expensive to install and to maintain. However, the patent is entirely silent with respect to any such type of adjusting mechanism.

Furthermore the mounting of the movable slats or rods and the mechanisms by which they are caused to follow the operating cams have heretofore presented serious problems due to the fact that the rod or slat is required to be biased both axially and radially in order to follow the cams. Even if the biasing problem is solved, the problem of friction between the cam and the bar still remains with increases in maintenance and operating expense resulting therefrom.

To recapitulate, prior art reels of the type comprising radially and axially movable rods or slats circumferentially alternating with fixed slats to define a cage like structure have heretofore suf-

2

fered from serious deficiencies in the mode of adjusting for storage time on the reel, i. e., adjusting the helix angle of the coils of thread on the reel, in the slat or rod mounting means and in several aspects of the cam following relationship existing between the cams and the slats moved thereby.

It is an object of this invention to overcome the foregoing deficiencies and to provide a thread storage, thread advancing reel in which the storage time of thread running on the reel is easily adjusted without requiring that the cam mechanism be driven, to provide a reel in which the rods are conveniently mounted for easy assembly and repair and to provide a reel in which friction between the cam following surfaces and the cams which act thereon is greatly reduced while the biasing mechanisms are both simplified in construction and reduced in number.

20 Other objects and advantages of this invention will be apparent upon consideration of the following detailed description of a preferred embodiment thereof in conjunction with the annexed drawings wherein:

25 Figure 1 is a vertical sectional view of a thread storage, thread advancing reel constructed in accordance with the principles of the present invention;

Figure 2 is a view in section taken on the line 2—2 of Figure 1;

30 Figure 3 is a view in section taken along the line 3—3 of Figure 1;

Figure 4 is a view in section taken along the line 4—4 of Figure 1;

35 Figure 5 is a view in section taken along the line 5—5 of Figure 1;

Figure 6 is a development of the eccentric and wobble plate shown in Figure 3 illustrating the phase relationship between the two; and,

40 Figures 7a, 7b and 7c illustrate the cyclic movement of a thread carrying bar in picking up, advancing and releasing a plurality of coils of thread.

Referring now in greater detail to the drawings, the reel of Figure 1 is comprised of sixteen slats 10 and 11 mounted respectively on bars 12 and 13, the configuration of which can be understood upon reference to Figures 1 and 2. The bars 12 and 13 and the slats 10 and 11 attached thereto are mounted in circumferentially spaced relation in suitable radial slots provided in discs 14 and 15, the bars 12 and 13 alternating circumferentially of the reel. The disc 14 is connected by screws 16, one of which shows in Figure 1, 55 to a flange 17 extending radially from a shaft

18 that constitutes the drive shaft for the reel and its principal support. The disc 15 is connected to the disc 14 by alternate bars 13 which tightly engage in the radial slots of both discs to act as spacers to determine the alignment and position of the disc 15. Set screws or an adhesive may be used to lock the bars 13 in position so that the only movement they are capable of executing is rotation with the discs 14 and 15 about the axis of the shaft 18.

The slots in which the alternate bars 12 are mounted afford sufficient clearance so that those bars are free to move both axially and radially with small clearance. The bars 12 are restrained radially by a pair of resilient bands 19 and 20 which surround the bars 12 and 13 at axially spaced points between the discs 14 and 15. The bars 13 are cut out at 21 so that the bands run as octagons between the bars 12 urging them resiliently radially inwardly toward the base of the slots in the discs 14 and 15 which accommodate them.

Each of the bars 12 is provided with four cam following surfaces, a pair of radial cam following surfaces 22 and 23 and a pair of axial cam following surfaces 24 and 25. These cam following surfaces are made by cutting shoulders in the radially inner part of the bar as can be easily understood upon reference to Figure 1. The cam following surfaces 22 to 25, inclusive, coact with a pair of rings 26 and 27 that are mounted respectively through roller bearing races 28 and 29 on eccentrics 30 and 31 which in turn are mounted on ball joints 32 and 33 for limited rocking movement. The ball joints 32 and 33 are keyed by set screws 34 and 35 to a sleeve 36 which surrounds the shaft 18 but which is not connected thereto.

If now reference is made to Figure 3, the configuration of the eccentric 30 can be understood. This eccentric is keyed to the ball 32 and the sleeve 36 by pins 37 and 38. By this arrangement the eccentric is completely unable to rotate with respect to either the sleeve 36 or the ball joint 32 but is free to rock back and forth about the axis of the pins 37 and 38. Since this rocking movement is permitted the ball race 28 can partake of it as well as the annulus or ring 26 which provides the cam surfaces for coaction with the cam following surfaces 22 and 24 on the bars 12. It is therefore to be noted that the angularity of the annulus 26 with respect to a plane normal to the axis of the shaft 18 is adjustable depending upon how the assembly is rocked about the axis of the pins 37 and 38. The construction just described in connection with Figure 3 is likewise adopted in connection with the annulus 27, the ball race 29, the eccentric 31 and the ball 33.

Between the two assemblies just described there is mounted on the sleeve or tube 36 a guiding block 39 which is keyed to the sleeve by a set screw 40. The guiding block 39 acts to guide a pair of identical pins 41 and 42 which extend through the block with their opposite ends engaging the eccentrics 30 and 31. The pins 41 and 42 are free to slide in the block 39 and serve to align the two eccentrics when either of them is tilted about its pins.

To adjust the eccentrics a block 43 is provided which surrounds the sleeve 36 and is keyed thereto by a set screw 44. This block is provided with two internally threaded holes lying 180° apart and in these holes are put externally threaded pins 45 and 46. The pins are provided

with a notch at the driving end to receive a screw driver and the block 43 is aligned with holes at 47 and 48 in the disc 15 so that access to the threaded pins 45 and 46 can be had without disassembly of the apparatus.

In the construction of the apparatus, the blocks 39 and 43 are so arranged circumferentially that the pins 41 and 45, 42 and 46 lie in the same diametrical plane of the sleeve 36, and at right angles to the diametrical plane of the pins 37 and 38 and their equivalents on the eccentric 31. It is now apparent that the angularity of the eccentrics 30 and 31 with respect to a plane normal to the long axis of the shaft 18 can be adjusted by adjustment of the threaded pins 45 and 46, the axial movement of which will be transmitted through the eccentric 31 to the pins 41 and 42 and from them to the eccentric 30. This arrangement permits easy adjustment and insures accurate tracking of the eccentric 30 when eccentric 31 is adjusted. Furthermore, by the use of two pins the arrangement is made self-locking in any position of adjustment.

With the foregoing description in mind, an understanding of the operation of the reel of the present invention can be had. In use, the shaft 18 is turned to produce a take-up speed that may be desired and the sleeve 36 is held stationary by any means not shown. As shaft 18 rotates thread 30 wound onto the reel around the slats 10 and 11 will form a generally helical body, the helix angle of which will be responsive to the magnitude of the tilt of the eccentrics 30 and 31 which may be adjusted by the set screws 45 and 46. As the reel rotates, successive bars 12 will be raised to the maximum radius of the eccentrics 30 and 31 and will be advanced and retracted axially in a cyclic path, the magnitude of which is dependent upon the adjustment of the screws 45 and 46.

It has been found that the phase relationship between the radial and axial movements of the bars 12 is highly important. If reference is made to Figure 3, it will be noted that, assuming counter-clockwise operation from the viewpoint of that figure, the maximum outward and inward radial movements of the bars 12 will be reached 45 degrees ahead of the maximum outward and inward axial movements of those bars. This phase of the invention can be well understood upon reference to Figures 6 and 7, wherein the relationship between two adjacent bars 11 and 12 is shown. In Figure 7a the bar 12 is shown in the position assumed at the limit of the outward radial movement at which time the thread running between two adjacent bars 12 is supported by the slats 10 and does not touch the intermediate slats 11 of the adjacent bars 13. As the bars 12 and 13 rotate in a counter-clockwise direction as viewed from the supported end, the bar 12 is gradually moved radially inwardly. During the first 45° of the radial inward movement the bar 12 continues to move axially away from its supported end and then, as the radial inward movement continues, the bar 12 begins to move axially toward its supported end until ultimately the thread is supported by the slats 11 of the adjacent bars 13.

As has been stated above, Figure 7a represents the position when a slat 10 of a bar 12 is with adjacent slats 10 supporting the thread. Figure 7b represents a transitional stage when the thread is in contact with slats 10 and 11 of adjacent bars whereas Figure 7c represents the condition when the thread is wholly supported by the slats 11 of stationary bars 13.

Figures 3, 7a, 7b and 7c can perhaps best be understood by reference to Figure 6 whereon the curve 49 represents the radial movement of a bar 12 and the curve 50 represents the axial movement thereof. The figure numerals 7a, 7b and 7c applied to these curves correlate with the slat positions shown in Figures 7a, 7b and 7c. As has been stated above, the radial movement leads the axial movement by 45° and this is clearly represented in Figure 6. Although the best results appear to be achieved when the radial movement leads the axial movement by about 45°, it may be desirable in some cases to alter this relationship in a small range, e. g., it may be slightly less than 45° or slightly more than 45°.

In the curve 50 the amplitude of the axial movement has been indicated as equal to the amplitude of the radial movement but, with the adjusting screws 45 and 46, it is apparent that the amplitude of the axial movement is adjustable to produce any desired coil spacing on the reel. The frequency of the advance of the thread is therefore fixed so long as the eccentrics 30 and 31 are not rotated but the magnitude or amplitude of the axial advance is responsive to the magnitude of the tilt of the eccentrics 30 and 31 so that helix angle adjustment is possible to permit variations in storage time of thread on a reel of any given length without modification of the take-up speed of that reel.

It will be understood that the eccentric 30, the ball race 28 and the ring 26 function so far as the following surface 24 is concerned as a wobble plate. Ring 27, ball race 29 and eccentric 31 similarly function with respect to following surface 25. Radial movement is imparted through the periphery of the rings 26 and 27 to the following surfaces 22 and 23. To cut down friction in the transmission of these movements, the anti-friction ball races 28 and 29 are employed. Thus the rings 26 and 27 are free to move with the bars 12 so that the eccentric is actually followed by the balls of the ball races in a substantially frictionless manner.

While no support has been shown for the sleeve 36, it is to be understood that whatever support is employed will be of the rigid cantilever type and will be applied to the right of the disc 15 as viewed in Figure 1. The support will be spacially arranged to permit access to the heads of the threaded pins 45 and 46 so that helix angle adjustments can be made by merely stopping the reel.

While the foregoing discussion has been wholly devoted to but a single embodiment of this invention, it is apparent that various modifications thereof will suggest themselves to those skilled in the art in view of the instruction afforded by the foregoing descriptions of a single specific example.

What is claimed is:

1. A thread storage, thread advancing device comprising a plurality of bars, means to support said bars from one end thereof in circumferentially spaced relationship to define a reel, means to rotate said supporting means about an axis in a plane normal to said axis, and means responsive to rotation of said supporting means to cause alternate bars successively to execute a cycle of movement including a radial reciprocation and an axial reciprocation out of phase by about 45° with the radial movement leading.

2. A thread storage, thread advancing device

comprising a plurality of bars, means to support said bars from one end thereof in circumferentially spaced relationship to define a reel, means to rotate said supporting means about a first axis, 5 a pair of eccentrics mounted for rocking movement about a second axis at right angles to said first axis and responsive to rotation of said supporting means to cause alternate bars successively to execute a cycle of movement including a radial reciprocation and an axial reciprocation, means to adjust one of said eccentrics to a desired angular position about said second axis and means to cause the other eccentric to track the movement of the adjusted eccentric.

10 15 20 25 30 35 40 45 50 55 60 65 70 75

3. A thread storage, thread advancing device comprising a plurality of bars, means to support said bars from one end thereof in circumferentially spaced relationship to define a reel, means to rotate said supporting means about an axis in a plane normal to said axis, means responsive to rotation of said supporting means to cause alternate bars successively to execute a cycle of movement including a radial reciprocation and an axial reciprocation out of phase by about 45° with the radial movement leading, and means to adjust the amplitude of the path of axial reciprocation.

4. A thread storage, thread advancing device comprising a plurality of bars, means to support said bars from one end thereof in circumferentially spaced relationship to define a reel, a shaft positioned along the long axis of said reel, means to mount said supporting means to said shaft, an eccentric mounted on said shaft for rocking movement about an axis at right angles to the long axis of the reel, a ring mounted on said eccentric and presenting an edge surface and a face surface, alternate bars of the circumferential group having following surfaces in contact with said edge and face surfaces respectively, means to hold said eccentric against rotation with said supporting means and adjustable means to hold said eccentric and hence said ring at a predetermined angularity with respect to said reel axis.

5. A thread storage, thread advancing device comprising a plurality of bars, means to support said bars from one end thereof in circumferentially spaced relationship to define a reel, a shaft positioned along the long axis of said reel, means to mount said supporting means to said shaft, an eccentric mounted on said shaft for rocking movement about an axis at right angles to the long axis of the reel, a ring, anti-friction bearing means supporting said ring from said eccentric, said ring presenting edge and face surfaces, alternate bars of the circumferential group having following surfaces in contact with said edge and face surfaces respectively, means to hold said eccentric against rotation with said supporting means and adjustable means to hold said eccentric and hence said ring at a predetermined angularity with respect to said reel axis.

6. A thread storage, thread advancing device comprising a plurality of bars, means to support said bars from one end thereof in circumferentially spaced relationship to define a reel, a shaft positioned along the long axis of said reel, means to mount said supporting means to said shaft, an eccentric mounted on said shaft for rocking movement about an axis at right angles to the long axis of the reel, a ring, anti-friction bearing means mounting said ring on said eccentric, said ring presenting an edge surface and a face surface, alternate bars of the circumferential group

having following surfaces, resilient means to hold said surfaces in contact with said edge and face surfaces respectively and means to hold said eccentric against rotation with said supporting means, the maximum deviation of said ring from a plane normal to said long axis lying 45° away from the maximum deviation of said eccentric from concentricity and lagging it in the rotation of the reel.

7. A thread storage, thread advancing device comprising a plurality of bars, a pair of axially spaced discs supporting said bars from one end portion thereof in circumferentially spaced relationship to define a reel, an axle for said discs, a sleeve concentrically surrounding said axle but held against rotation therewith, a pair of eccentrics mounted on said sleeve in axially spaced relationship between said discs, means mounting said eccentrics on said sleeve for rocking movement about an axis at right angles to the sleeve axis, a pair of rings, a pair of anti-friction bearings, each antifriction bearing supporting one of said rings from one of said eccentrics, said rings presenting edge and face surfaces, alternate bars of the circumferential group having following surfaces engaging the edge surfaces of the rings and also engaging the adjacent face surfaces of said rings, resilient bands biasing said alternate bars of the circumferential group radially inwardly, a mounting block on said sleeve, a pair of set screws in said mounting block in bearing relation to one of said eccentrics to move the same to a desired angular position about the axis at right angles to the sleeve and means to cause the other eccentric to track the movement of the eccentric against which the screws act.

8. A thread storage, thread advancing device as claimed in claim 7 in which the tracking means comprises a pair of pins of equal length extending between said eccentrics, said pins lying 180° apart and 90° from the means which mount the

eccentrics for rocking movement about an axis at right angles to the reel axis.

9. A method of storing thread while advancing the same that comprises continuously drawing thread from a source, forming succeeding portions thereof into a generally helical configuration, moving succeeding portions of each coil of the helix radially outwardly and axially away from the zone of origin of the helix in a cycle characterized by the radial movement and the axial movement being out of phase with the radial movement leading by about 45°.

10. A method of storing thread while advancing the same that comprises continuously drawing thread from a source, forming succeeding portions thereof into a generally helical configuration, moving succeeding portions of each coil of the helix radially outwardly and axially away from the zone of origin of the helix in a cycle characterized by the radial movement and the axial movement being out of phase with the radial movement leading by about 45°, the maximum radial movement outwardly occurring in the same radius of the helix throughout each cycle.
